INTERNAL COMBUSTION ENGINE

Jean Edouard Andreau, Paris, France, assignor
to "S. E. B. A., Societe Anonyme d'Exploita-
tion de Brevets d'Automobiles", Glarus, Swit-
zerland, a society of Switzerland

Application April 10, 1935, Serial No. 15,657
In Belgium April 14, 1934

11 Claims. (Cl. 123—48)

The present invention relates to internal combustion engines and also to vehicles, such as automobile vehicles (on road or on rail) or aircrafts, provided with such engines.

Up to the present time, engines of this kind had, in a general way, a cylinder capacity and a clearance space which were geometrically fixed. It follows from this arrangement that the utilization of the gases admitted into the engine 10 is very bad for low loads.

The reason is that, for such loads, it is necessary to utilize a considerable portion of the compression stroke for restoring atmospheric pressure in the cylinder and that the true ratio of compression decreases more and more as the load decreases.

The consumption of fuel then increases, becoming as high as 700 or even 800 grammes per horse-power hour for the engines of motor-cars running at speeds ranging between 20 and 30 20 kms. per hour.

The object of the present invention is to provide an engine of the type above referred to in which the drawbacks above mentioned are obviated.

The essential feature of the present invention consists in providing an engine of the type above referred to with means whereby the volumetric ratio of compression is automatically varied 30 within certain limits in such manner as to keep the true ratio of compression substantially constant under all conditions of working of the engine corresponding with these limits.

Other features of the present invention will 35 be apparent from the following detailed description of some specific embodiments thereof.

Preferred embodiments of the present invention will be hereinafter described, with reference to the accompanying drawings, given merely by way of example, and in which:

Fig. 1 is a diagrammatic view of a cylinder and its piston, serving to illustrate the principle of the present invention;

Fig. 2 is a diagrammatic axial sectional view 45 of the head of a cylinder made according to the present invention;

Figs. 3 and 4 are views similar to Fig. 2, showing two other embodiments of the device according to the present invention;

Fig. 5 is a diagrammatic view of a system including an engine and means for controlling said engine, the whole being devised according to the present invention, the view being in 55 general a plan view but many of the parts being

shown in section, while the intake manifold is shown in elevation, for the sake of clarity;

Fig. 5a is a fragmentary top view of the control mechanism of the throttle valve 23 shown in Fig. 5.

Fig. 6 shows a modification of the system of Fig. 5, this modification being more especially intended for aircraft engines;

Let us first consider a normal engine, as shown in Fig. 1, in which the piston 1 moves between an upper extreme position A and a lower extreme position B while the plane O represents the lower face of the cylinder head. Let it be first assumed that this engine is running under normal conditions (the throttle valve full 10 opened). During the compression stroke, atmospheric pressure is established in the cylinder when the piston is at level B' not very far from point B. The true ratio of compression is 15 then

$$\frac{OB'}{OA}$$

This ratio of compression may be, for instance, 20 6 to 1.

On the contrary, when the engine is running with the throttle valve closed or nearly closed, there is a considerable degree of vacuum in the intake pipe and, consequently, when the piston passes the position B' during the compression stroke the pressure of the charge is even lower than atmospheric pressure. A supplementary piston travel B'B'' is therefore necessary before atmospheric pressure is restored in the cylinder. In this case the true ratio of compression is 25 30 35 equal to

$$\frac{OB''}{OA}$$

that is to say much lower than in the preceding case. It may even happen that the pressure in 40 the cylinder at the end of the compression stroke is lower than atmospheric pressure.

If, under the last mentioned conditions of running, the cylinder head had been in position O', that is to say at a level lower than O, then 45 the ratio of compression would have been

$$\frac{O'B''}{O'A}$$

and therefore might have been made equal to the 50 desired value (for instance 6 to 1) by suitably choosing position O'.

In such an engine, the effective cylinder capacity, would correspond to the stroke AB'', and, furthermore, in the course of the expansion 55

stroke, the piston of such an engine, instead of stopping at B'', as would be the case with the piston of an ordinary engine of the same compression ratio, moves further down as far as the vicinity of B' (normal exhaust opening). It follows that the ratio of expansion, and therefore the efficiency, is the higher as the charge is smaller.

According to the present invention, an internal combustion engine of any kind whatever, for instance a multi-cylinder combustion engine for an automobile vehicle, is provided with means whereby the volumetric ratio of compression of said engine varies automatically within certain limits so as to maintain the true ratio of compression constant for all conditions of filling of the engine cylinders corresponding with these limits, which are preferably wider apart than the limits of utilization.

I have found that the desired result can be obtained in a particularly advantageous manner by making the cylinder head of each cylinder movable with respect thereto.

This arrangement is particularly well adapted for use with sliding valve engines, and especially engines of this kind including a single sliding sleeve valve.

This is due to the fact that, in sliding valve engines, an arbitrary position of the cylinder head is admissible, this position being quite close to the piston if necessary, provided that the inlet and outlet ports are suitably devised.

It should be noted that in the case of sliding valve engines having a single sliding sleeve valve, the latter is guided by the cylinder, the cylinder head (or stationary piston) being entirely free to move.

In the following description, it will be assumed that the engine is of the sliding valve type with a single sliding sleeve valve.

According to the embodiment shown by Fig. 2, the cylinder head 3 of each cylinder of the engine is mounted in such manner, with respect to said cylinder, that it can be given translatory displacements parallel to the axis of said cylinder.

Said cylinder head 3 is provided with a screw threaded outer wall 4, the threads being preferably irreversible, and on this part 4 there is screwed a nut 5 integral with a control lever 6. This nut can be given only rotary displacements owing to the provision of an upper stop 7 and a lower stop 8, both carried by the upper part of the cylinder.

It will be readily understood that, with such an arrangement, by acting on lever 6, nut 5 is caused to turn and consequently the cylinder head 3 is caused to move either upwardly or downwardly.

In order to cool said cylinder head, I advantageously provide a cooling jacket communicating with the water circulation of the engine, for instance through screwed tubes 9 and 10.

In the embodiment illustrated by Fig. 3, the cylinder head is controlled by means of a system of wedges 11 which can be given translatory displacements.

In the embodiment illustrated by Fig. 4, the cylinder head is actuated by means of a cam 12. Springs 13, of sufficient strength, are provided for keeping the cylinder-head applied against said cam, or any other equivalent organ, when the latter does not exert an operative action in both directions.

In order to obtain the engine proper accord-

ing to the present invention, I provide means for controlling the position of the cylinder heads in accordance with the load of the engine as indicated by the manifold suction.

Assuming, for instance, that the engine includes four cylinders (Fig. 5) and that the cylinder heads are controlled through a device of the kind shown by Fig. 2, the free ends of the respective levers 6 may be all operatively connected to a longitudinal control piece 14, springs 10 such as 15 and 16 being provided in connection with each arm 6 as shown in the drawings, that is to say in a manner similar to the arrangement used in steering gears.

Owing to the presence of these springs, the organ that acts on control member 14 shall not be required to displace the cylinder heads while the latter are subjected to the maximum pressures of the cycles.

This is due to the fact that the cylinder heads 20 are subjected to the action of alternating forces and can therefore be caused to undergo elementary displacements nearly without resistance during the favorable periods of the cycles. In this manner, the displacement of the cylinder heads, which necessitates several cycles, if it is of a certain amplitude, takes place very easily.

I have found that it is advantageous, in order to move control member 14, to make use of a servo-motor 17, of any kind whatever. For instance, according to the embodiment of Fig. 5, this servo-motor includes a piston 18 which is subjected, on either of its faces according to the position of a slide valve 19, to the action of oil under pressure fed either by a usual compression pump, or, preferably, by an accumulator having an air cushion at the top, 20, in which a pump 21 maintains, at any time, a reserve of oil under pressure sufficient for ensuring a certain number of complete strokes of member 14, for instance ten of these strokes.

Thus, according as the slide valve 19 is displaced in one direction or in the opposite direction, the volumetric ratio of compression of all the cylinders of the engine will vary in one direction or the opposite one.

It suffices, now, to establish for the control of said slide valve 19, a device such that the condition above stated is complied with.

Theoretically, if the variations of load and speed of the engine were sufficiently slow, it would suffice to control slide valve 19 through a manometric box subjected to the suction existing in the intake pipe of the engine beyond the throttle valve, for obtaining the desired working, provided, of course, that the whole is devised in such manner that, at least within certain limits, to each value of this suction there corresponds, for the engine, a volumetric ratio of compression, itself corresponding to the desired true ratio of compression.

But every time the variations of load and speed of the engine must be quick, which is, for instance, the case with automobile vehicles, it is necessary, in order to avoid accidents as might result from excessive ratios of compression (due for instance to the fact that, in the case of a sudden opening of the throttle valve, the cylinder heads would not move upwardly sufficiently quickly), to submit the cylinder heads to the action of the organ that controls the admission of fuel mixture to the engine (and which will be hereinafter called throttle pedal). This operative connection between the throttle pedal and the cylinder heads is so devised that, in the

case of a variation of the rate of feed of fuel mixture, the operation that produces this variation causes the cylinder heads to move upwardly, the throttle valve opening gradually in the course of this upward movement of the cylinder heads until it reaches the position of opening that corresponds to the position given to the pedal throttle.

In the embodiment of Fig. 5, I have shown, 10 besides control member 14 and servo-motor 17, the intake pipe 22, its throttle valve 23, and also the throttle pedal 24.

On pipe 22, beyond throttle valve 23, I provide a manometric box 25 communicating with 15 said pipe and including a diaphragm 26.

I fix to control member 14, on the one hand an element 27 adapted to limit the displacements of a lever 28 keyed on the spindle of the throttle valve in the direction that corresponds to the 20 opening of said throttle (so that the opening of said throttle can never be greater than that corresponding to the actual position of the cylinder heads) and, on the other hand, an element 29 carrying, at its end a pivot 30 for a lever 31 25 a suitable point 32 of which is connected, for instance through an articulated rod 33, with slide valve 18.

Throttle valve 23 is thus controlled through 30 lever 28, which is itself engaged at its upper end 28a in a slot 34 carried by a piece 34a operatively connected with throttle pedal 24. Therefore said throttle pedal can be moved in the direction corresponding to the opening of the throttle even when said throttle is prevented from opening at 35 this time by the fact that lever 28 is in contact with element 27.

This throttle is further subjected to the action of a spring 35 tending to open it.

Finally I interpose, between throttle pedal 24 40 and the free end of lever 31, a connecting rod 36 an intermediate point 37 of which, for instance its middle point, is operatively connected with diaphragm 26.

The system above described works in the following manner:

Supposing, first, that the throttle pedal is acted upon for opening the throttle valve, the end of lever 28 being in contact with element 27, the throttle valve 23 is not influenced. Point 37 remaining stationary, the end of lever 31 is moved counter-clockwise in the direction that produces, 50 through servo-motor 17, the upward movement of the cylinder heads. But, at the same time, pivot 30 is moved through the action of the servo-motor 17 in such manner as to bring back slide valve 18 into its neutral position and the servo-motor stops. During this time, the element 27 against which lever 28 was applied also moves, 55 thus permitting the throttle to open the desired amount. The engine therefore gives a greater torque than before.

If now, on the contrary, the throttle valve is 60 acted upon in such manner as to close the throttle valve, the operations above described take place in the reverse order, but in this case the throttle valve is closed directly by the throttle pedal and the rate of feed is immediately reduced. The displacement of the cylinder heads is then facilitated by the action of diaphragm 65 26 and the clearance spaces in the cylinders of the engine are reduced until they correspond with the new position of the throttle.

If, contrary to what has been assumed up to 70 now, the throttle 24 is stationary and the speed of revolution of the engine increases because the

resistance decreases, the suction increases, the diaphragm of box 25 acts on point 37, so as to produce a reduction of the clearance spaces and to reduce the torque. The movement of control member 14 produces, through the displacement of pivot 30, the return of slide valve 18 to its neutral position, at the same time as element 27 reduces the opening of the throttle valve to the proper degree.

An equilibrium is thus established which corresponds to a lower rate of feed and the automatic regulation of the capacity of the cylinders and of the torques is obtained.

In the preceding description I have been referring to the case of internal combustion engines. The invention is of course applicable to any type of such engines, provided that they include a simultaneous control of air and fuel.

Thus these engines will no longer require the pumping of air which is necessary at the present time under low loads. This pumping reduced the efficiency and prevented the fuel from being utilized under the optimum conditions.

When applied to aircraft engines, the present invention makes it possible to obtain a better utilization of the fuel at all altitudes.

It suffices, in this case, in order to obtain the desired effect, to complete the mechanism shown by Fig. 5 by adding thereto a manometric box 39 (Fig. 6) the diaphragm of which is mechanically connected with point 37 and inside which the pressure is equal to the atmospheric pressure on the ground level.

This box then dilates more and more as the external pressure decreases and acts in the same manner as an increase of the suction in the intake pipe of the engine, that is to say reduces the clearance spaces and restores the normal pressure of explosion.

This solution is believed to be superior to the usual constant under-feed or to the provision of compressors.

When devising an automobile vehicle according to the present invention, it will be preferable to interpose, between the engine and the driving 45 wheels an automatic clutch 38, for instance of the hydraulic type, capable of transmitting the maximum torque of the engine when the vehicle is stationary. I may, for this purpose, make use of a clutch such as those called "fluid fly-wheels". 50 which ensure a nearly complete release at very low speeds.

It is thus possible to wholly dispense with a change speed device and to have a wholly automatic control of the vehicle, since the driver is 55 concerned merely with the throttle pedal (or the equivalent) and the brake.

According to the present invention, an automobile vehicle provided with an engine such as that above described may be streamlined in such 60 manner as to reduce the head resistance.

As a matter of fact, one of the most characteristic drawbacks of streamlined bodies for automobile vehicles is that said vehicles are nearly always running (except for the maximum speed 65 corresponding to the maximum power of their engine) with a power substantially lower than said maximum power.

Thus, with an ordinary engine, the specific consumption is not so good, for a given speed, 70 than if the vehicle were not streamlined, since the throttle valve is less opened and therefore the true ratio of compression is lower. Therefore, due to the fact that the fuel is not so well utilized, a portion of the benefit obtained by the reduction 75

of the power necessary for propelling the vehicle is lost.

On the contrary, with an engine according to the present invention, as the specific consumption is not influenced in a detrimental manner by the reduction of the load, it is possible to obtain the maximum benefit of the advantages of streamlined bodies and the consumption of fuel will remain very low at all speeds.

10 In a general manner, while I have, in the above description, disclosed what I deem to be practical and efficient embodiments of the present invention, it should be well understood that I do not wish to be limited thereto as there might be 15 changes made in the arrangement, disposition and form of the parts without departing from the principle of the present invention as comprehended within the scope of the accompanying claims.

20 What I claim is:

1. An internal combustion engine comprising means forming a compression chamber the size of which is capable of being changed, a power piston movable in said chamber, a valve for feeding fuel to said chamber, means for effecting a change in the size of said chamber and for operating said valve when the size of the chamber has been changed, means for delaying the motion of said changing means and a one-way connection between said changing means and said valve, whereby said changing means will operate said valve directly only when said changing means move in one direction.

2. An internal combustion engine comprising means forming a compression chamber, a piston movable in said chamber, regulating means for varying the size of said chamber and including a member movable in said chamber, a valve for feeding a fuel mixture to said engine, and actuating means connected to said regulating means and movable in one direction for enlarging the compression chamber and in the opposite direction for reducing the same, means connecting said actuating means to said valve and comprising a one-way connection for moving said valve toward open position when the compression chamber is enlarged and for engaging the valve with said connecting means for moving the same toward closed position when the compression chamber is reduced.

3. In an internal combustion engine according to claim 2, having an intake manifold, means connected to said manifold and said regulating means for automatically controlling said regulating means and said valve, said control means being under the influence of and operated by variations in the degree of vacuum in said manifold.

4. An internal combustion engine according to claim 2, means for automatically adjusting said regulating means and said valve, said means being under control of the pressure of the outer atmosphere for adjusting the size of said compression chamber and adjusting said valve in accordance with variations of said pressure.

65 5. An internal combustion engine according to claim 2 having an intake manifold, said actuating means comprising an element for automatically controlling said regulating means and said valve, said element being under the influence of and operated by variations in the degree of vacuum in said manifold, means for automatically adjusting said regulating means and said valve, said adjusting means being under control of the pressure of the outer atmosphere for adjusting the

size of said compression chamber and adjusting said valve in accordance with variations of said pressure.

6. An internal combustion engine according to claim 2, further comprising resilient means connecting said movable member to said regulating means for delaying the movement of said member in said compression chamber when the pressure within said chamber exceeds a certain limit.

7. An internal combustion engine comprising means forming a compression chamber, a piston movable with a reciprocating motion in said chamber, regulating means for adjusting the size of said compression chamber and including a member movable in said chamber, a valve for feeding fuel mixture to said engine, and actuating means connected to said regulating means and movable in one direction for enlarging said compression chamber and in opposite direction for reducing the size of said chamber, means integrally connected with said regulating means for controlling the degree of opening of said valve, means connected to said valve for normally holding the same in opened position and in contact with said control means, said valve being independent of the movement of said actuating means for enlarging the compression chamber, and means independent of the movement of said regulating and control means, for operatively connecting said valve to said actuating means during 30 said reducing movement.

8. In an internal combustion engine according to claim 7, said independent means comprising an element slidably arranged with respect to said valve and being secured to said actuating means, whereby, at the movement of said actuating means for enlarging the compression chamber, said element slides with respect to said valve leaving the same unactuated thereby.

9. In an internal combustion engine according to claim 7, said independent means comprising an element slidably arranged with respect to said valve and being secured to said actuating means, whereby, at the movement of said actuating means for enlarging the compression chamber, 45 said element slides with respect to said valve leaving the same unactuated thereby, said element having a stop at one end thereof whereby, at the movement of said actuating means for reducing the size of the compression chamber, 50 said stop immediately moves said valve toward a closing position.

10. An internal combustion engine according to claim 2, said regulating means including a system of levers and a servo-motor including a slide valve connected to said levers, whereby upon movement of said actuating means, said slide valve is returned to a neutral position as soon as the compression chamber has been adjusted to the desired extent.

11. An internal combustion engine having means forming a compression chamber, means for adjusting the size of said chamber, said means comprising a servo-motor, a member actuated by said servo-motor, a mechanism operatively connected with said chamber for varying the size thereof, and resilient means interposed between said mechanism and said member connecting the same for delaying the varying movement of said mechanism when the pressure within 70 said combustion chamber exceeds a certain limit, said resilient means being operative in both directions of movement of said adjusting means.

JEAN EDOUARD ANDREAU.
